COVE BASE

John Hays Waterman, Salinas, Calif.

Application October 14, 1940, Serial No. 361,056

9 Claims. (Cl. 4—1)

This invention relates in general to the finish of the floor covering with a bathroom fixture at the floor, and in particular the invention is directed to, and it is my principal object to provide an arrangement whereby cove bases may be conveniently employed as the floor finish with bathroom fixtures such as bath tubs, pedestal type wash basin, and toilets.

Another object of the invention is to provide a cove base finish with bathroom fixtures at the floor, which is sanitary, easy to clean, neat in appearance, and provides toe room when the cove is inset relative to the fixture.

It is also an object of the invention to provide a cove base assembly for toilets, which permits of placement or removal of the toilet bowl after the cove is in place.

A further object of the invention is to produce a simple and inexpensive cove base and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a fragmentary transverse section showing an inset linoleum cove base as applied to a bathtub in accordance with my invention.

Figure 2 is a similar view but with the cove base substantially flush with the bathtub skirt.

Figure 3 is a fragmentary transverse section showing a tile cove base as I apply the same to a bathtub.

Figure 4 is a fragmentary transverse section of my linoleum cove base assembly for a toilet.

Figure 5 is a fragmentary transverse section of such cove base assembly as embodying a tile cove.

Referring now more particularly to the characters of reference on the drawings, and at present to Figs. 1—3 inclusive, which disclose the invention as applied to a bathtub, the numeral 1 indicates a bathtub including, as usual, an inner wall 2 and an outer substantially vertical skirt 3 spaced therefrom.

The skirt 3 terminates at its lower horizontal edge 4 some distance above the floor 5 which as usual rests on a sub-floor 6. The space between skirt 3 and wall 2 is closed adjacent edge 4 by means of a horizontal filler plate 7 having an upturned flange 8 along one edge frictionally engaging the inner face of skirt 3, and a downturned flange 9 along the other edge frictionally engaging the adjacent face of wall 2 and depending to

adjacent but short of floor 5. These flanges may be secured to the skirt and wall in any suitable manner if desirable.

For an inset linoleum cove base, as shown in Fig. 1, the linoleum 10 which covers floor 5 is extended to a point relatively close to wall 2, thence curves upward as at 11, and then lies flat as at 12, against flange 9; the edge of the linoleum terminating substantially at the bottom of filler plate 7. A suitable molding 13 is disposed beneath and supports the curved portion 11.

When a substantially flush cove base of linoleum is desired, it is formed as shown in Fig. 2; a blocking member 14 being engaged between plate 7 and floor 5, and portion 12a of the linoleum resting thereagainst as shown. Here the upper edge of the linoleum engages behind and slightly underlaps edge 4 of skirt 3.

In Fig. 3, I illustrate a semi-inset tile cove base. A blocking member 15 is disposed between plate 7 and the sub-floor 6 and engages flange 9; reinforced cement 16 covering the sub-floor and outer face of blocking member 15. The floor tiles 17 are placed as usual, while the cove tile 18 abuts against the cement on blocking member 15 and extends up to plate 7. If a flush tile cove base is desired, the blocking member 15 is moved outward, while for greater inset such member is omitted or reduced in thickness.

Turning now to the embodiment of the invention shown in Fig. 4, I disclose here a linoleum cove assembly for a toilet. A separate base 19 is set at the time of roughing in on the floor 5, and the lead ferrule or discharge pipe extends upward through a throat 21 in said base; such base being secured to the floor by any suitable type bolts as at 22. The top of this separate base is of a configuration and size in plan the same as the base portion 23 of the toilet bowl 24, and is also formed to match; being secured thereto by bolts. The ferrule is connected as usual and the channel 25 filled with sealing putty. It is to be noted that the heads of bolts 22 are disposed so as to enter such channel.

About its periphery and a short distance below the top, the separate base 19 is reduced in size in the manner of an undercut, as indicated at 26. The linoleum 27 curves upward adjacent the vertical wall of the undercut, as at 28, and thereabove rests flat against said wall up to the horizontal portion of said undercut.

In Fig. 4, a tile cove base for a toilet is illustrated, and in this form the assembly of separate base 29 and bowl base 30 are the same as shown in Fig. 3, except that the separate base is slightly

higher and seats on the sub-floor 6. Reinforced cement 31 covers the sub-floor and lines the vertical wall of the base undercut; the floor tile 32 being set as usual and the cove tile 33 being disposed in the undercut and extending up said vertical wall to the horizontal face thereof.

The advantages of my improved cove base assembly for bathtubs and toilets are that such assembly is sanitary, easy to clean, watertight, convenient, provides ample foot room adjacent the fixture, and assures a neater appearing floor as the cove base for the fixture matches with and eliminates any break in the cove base, which may extend about the entire room.

In addition, the cove base assembly as applied to a toilet simplifies removal of the toilet bowl for inspection and repairs, as the separate base is left secured to the floor.

From the foregoing description it will be readily seen that I have produced such a cove base as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In combination, a toilet bowl having a base, a floor, an initially separate base seated on the floor and supporting the bowl base; said separate base having a peripheral undercut thereabout immediately above the floor, and a floor covering extending into said undercut and thence curving upwardly as a cove.

2. In combination, a toilet bowl having a base, a floor, an initially separate base seated on the floor and supporting the bowl base, said separate base having a peripheral undercut thereabout immediately above the floor, a tile floor covering extending to a point adjacent said separate base and a tile cove continuing from said point into the undercut and up to the top thereof.

3. A cove base between a floor and a wall of a fixture, said wall including spaced inner and outer wall portions, the inner wall portion extending substantially to the floor and the outer wall portion terminating at its lower edge in clearance relation to the floor; said cove base comprising an initially separate filler member disposed between said wall portions adjacent the lower edge of said outer wall portion, and a floor covering extending over the floor to a point adjacent said inner wall portion and thence extending up the latter to substantially said filler member.

4. A cove base between a floor and a wall of a fixture, said wall including spaced inner and outer wall portions, the inner wall portion extending substantially to the floor and the outer wall portion terminating at its lower edge in clearance relation to the floor; said cove base comprising an initially separate filler member disposed between said wall portions adjacent the lower edge of said outer wall portion, said filler member com-

prising a substantially horizontal plate having an upturned flange along one edge engaging the inner face of the outer wall portion and a downturned flange along the other edge engaging the adjacent face of the inner wall portion.

5. A cove base between a floor and a wall of a fixture, said wall including spaced inner and outer wall portions, the inner wall portion extending substantially to the floor and the outer wall portion terminating at its lower edge in clearance relation to the floor; said cove base comprising a filler member disposed between said wall portions adjacent the lower edge of said outer wall portion, a blocking member between said filler member and the floor outwardly of the inner wall portion, and a floor covering extending to a point adjacent said blocking member and thence curving upwardly as a cove and resting against the outer face of said blocking member.

10 6. A cove base between a floor and a wall of a fixture, said wall including spaced inner and outer wall portions, the inner wall portion extending substantially to the floor and the outer wall portion terminating at its lower edge in clearance relation to the floor; said cove base comprising an initially separate filler member disposed between said wall portions adjacent the lower edge of said outer wall portion, said filler member comprising a substantially horizontal plate having a downturned flange along its inner edge engaging the adjacent face of the inner wall portion, and a linoleum floor covering extending to a point adjacent said inner wall portion, thence curving upward and resting in part on said flange.

25 7. A cove base between a floor and a wall of a fixture, said wall including spaced inner and outer wall portions, the inner wall portion extending substantially to the floor and the outer wall portion terminating at its lower edge in clearance relation to the floor; said cove base comprising an initially separate filler member disposed between said wall portions adjacent the lower edge of said outer wall portion, a blocking member between said filler member and the floor, a floor covering extending to a point adjacent the blocking member and thence curving upward as a cove and resting against said blocking member; the upper edge of said cove projecting between and being closely engaged by the lower edge portion of the outer wall portion and said blocking member.

30 8. A structure as in claim 3 in which the floor covering is of tile; the upwardly extending portion of the covering being a tile cove terminating at its upper edge in engagement with said filler member.

35 9. A structure as in claim 3 in which the floor covering is of tile; the upwardly extending portion of the covering being a tile cove terminating at its upper edge in engagement with said filler member; there being an initially separate blocking and backing member engaged between the tile cove and said inner wall portion, said blocking and backing member extending from the filler member to the floor.

JOHN HAYS WATERMAN.
